SIGN

Gerald P. Murphy, Cleveland, Ohio

Application September 15, 1941, Serial No. 410,822

5 Claims. (Cl. 40—145)

This invention relates to signs and, more particularly, to a sign frame and mounting means for street signs and the like.

In most cities it would be advantageous to be able to mount street signs on corner telephone poles, lamp posts, and the like, but throughout the various areas of cities such poles will vary in diameter and shape, so that heretofore it has been necessary to design special street sign frames for each type of pole found throughout the city. It is an object of this invention, therefore, to provide a readily mountable street sign which may be mounted on any type of pole, regardless of the diameter or configuration. Further, heretofore street sign frames have tended to be ornate. The disadvantages of such sign frames were that they were not only expensive, but afforded cracks and crevices which would receive and collect moisture, thereby promoting the corrosion of the sign and sign frames. Street sign frames and supports employed heretofore also generally failed to protect the edges of the sign plates which were the most likely portions of the sign plates to become injured. It is another object of this invention, therefore, to provide a simple sign support which may be economically constructed and which will adequately protect the sign plates while providing a minimum of crevices and surfaces for the collection of moisture.

Other objects and advantages will be apparent from the following specification, claims, and drawings, in which:

Fig. 1 is a vertical elevation taken along the line 1—1 of Fig. 2, showing my sign and frame secured to a pole.

Fig. 2 is a horizontal section taken along the line 2—2 of Fig. 1.

Fig. 3 is a vertical elevation of my sign frame as shown in Figs. 1 and 2.

Fig. 4 is a plan view of a modified sign.

Fig. 5 is a vertical elevation of the modified sign shown in Fig. 4.

In the drawings, in which like reference characters refer to like parts, the preferred sign frame 10, as shown in Figs. 1 to 3, is comprised of a T-section strap 11 having a center flange. The frame 10 is very strong and is formed very simply by mitering out the center flange at the points where the strap 11 is bent to form the rectangular frame 10, the ends of the strap 11 being welded together by the weld 12, as shown in Figs. 1 and 3. With the frame 10 thus formed, it will be provided with a top flange 13, bottom flange 14, front flange 15, and back flange 16. As shown most clearly in Fig. 3, however, the back flange 16 does

not extend to the corners of the frame 10, the corner portions of the flange 16 being cut away to provide fastening strap openings 17 and 18.

A stiff curved spring steel post plate 20 is fastened to the back side 19 of the frame 10 adjacent the back flange 16, by welding or other suitable means. The radius curvature of the post plate 20 is less than the radius of curvature of any post to which the sign is likely to be attached and the frame 10 is attached to the convex surface of the plate 20. It is this curved post plate 20 which permits the sign to be attached securely to any post.

The frame 10 is particularly adapted to carry a double plate sign, that is, a sign made up of two sign plates, each having printing on only one side and positioned back-to-back in the frame. Thus, as shown in Figs. 1 and 2, the backs of the sign plates 22 are placed against the flanges of the frame 10 and are secured thereto by suitable means, such as the bolts 23 and 24, in the flanges 15 and 16, respectively. Thus, the flanges 13, 14, 15, and 16 serve to space the sign plates 22 from each other and to support the edges of the plates. The edge support afforded by the flanges is particularly advantageous when the sign plates 22 are made of glass or like brittle material. The spacing afforded by the flanges is advantageous in reducing corrosion when the sign plates 22 are made of metal. In mounting the sign plates 22 within the frame 10, care should be taken to space the plates from the back side 19 so that the fastening strap openings 17 and 18 are not closed off.

To mount the frame 10 on a post 30, fastening straps 31 are passed through the openings 17 and 18, the ends of each of the straps 31 being secured in the turnbuckle clamps 32. The fastening straps 31 are then passed around the post 30 and the clamps 32 are joined together by the turnbuckle bolts 33. As the straps 31 are tightened by the bolt 33, the spring plate 20 is spread until it is nearly flush with the surface of the pole 30, as shown in Fig. 2. By making the spring plate 20 relatively stiff, ample frictional engagement by the plate 20 and the straps 31 with the pole 30 is insured to maintain the sign in its desired position on the pole. At the same time, the plate 20, being held between the straps 31 and the pole 30, affords ample lateral support for the frame 10 to prevent its being turned, with the back side 19 of the frame as an approximate axis, on the pole 30.

From the foregoing it is apparent that the spring plate 20, when spread, will always main-

tain the straps 31 under tension. Thus, if the straps 31 are stretched or otherwise slightly loosened by wind loads, for example, the plate 20 will take up any slack in the straps 31 and maintain the straps 31 tight around the pole 30. The spring plate 20 will perform its function of tensioning the fastening strap on a pole or post of any configuration except where the curvature of the pole is identical with the natural set of the spring plate. This contingency may be avoided, however, by reversing the curvature of the plate 20 shown in the drawings or by making the plate 20 of an irregular configuration.

It is also apparent from the foregoing, that the frame 10 may be mounted in a horizontal position on substantially any type of vertical post. If the post is tapered, one of the fastening straps will simply be tensioned less than the other. If the post is fluted, the edges of the plate 20 will either be mechanically engaged in the flutings or rest upon the unfluted surface of the post in the same manner in which it rests upon the surface of an unfluted post.

It is obvious that for stability preferably two fastening straps, rather than one, are employed to mount the frame 10 on a post. Insofar as the circumference of a post will accommodate a plurality of post plates and fastening means for the fastening straps, any number of signs may be fastened by one or a pair of fastening straps. A preferred manner of mounting two signs on one post, however, is shown in Figs. 1 and 2. By employing a common fastening strap 31 which passes through the upper fastening strap opening in one sign and the lower strap opening in the other sign, each sign thus may be further secured by a separate strap carrying a portion of the load imposed by only one sign. This manner of securing two signs to one post is obviously more economical than employing a separate pair of fastening straps and has been found to be equally secure.

Another modification of my sign frame, as shown in Figs. 4 and 5, is particularly designed for a single sign plate, that is, a sign plate carrying printing on both sides. As shown in Figs. 4 and 5, the frame 110 is comprised of a flat strap 111 bent into a rectangular form and butt welded at the back side 119 of the frame. A spring plate 20 is welded or otherwise secured to the frame 110 in the same manner as the spring plate 20 is secured to the frame 10. Lugs 115 and 116 are welded or otherwise secured to the inside of the front and back sides of the frame 110. It should be noted that these lugs are oppositely offset in a clockwise direction from the vertical center plane of the frame. Thus, when the sign plate 122 is secured in the frame, it lies in the vertical center plane of the frame and only a right-hand end portion of each face of the sign plate will be obscured by a lug 115 or 116. Consequently, only the least important end of a street sign, for example, will be obscured by the fastening lug.

From the foregoing, it is apparent that either modification of my sign frame affords a projecting rim which protects the edges of the sign plate from injury and that there are a minimum of recesses and crevices for the collection of moisture which would promote corrosion.

From the foregoing, it is also apparent that this invention is not restricted to the particular embodiments disclosed, but may be modified, either in whole or in part, by those skilled in the art. This invention, therefore, is limited, not to the specific uses and embodiments disclosed, but by the following claims.

What is claimed is:

1. In a sign, a post, a sign frame, a laterally extending spring plate integral with said sign frame adjacent said post, said spring plate having a curvature incongruent with said post, portions of adjacent surfaces of the post and spring plate being spaced from each other when said spring plate is unstressed, and a fastening strap extending around said post, through said frame and over said spring plate.

2. In a sign, a post, a sign frame, a laterally extending spring plate integral with said sign frame and engaging said post, said spring plate having a curvature incongruent with said post, portions of adjacent surfaces of the post and spring plate being spaced from each other when said spring plate is unstressed, a fastening strap extending around said post and connected with said sign frame, and adjustable fastening means to tighten said strap around said post and hold said spring plate in a deflected position against said post.

3. In a sign, a post, a first sign frame, a spring plate integral with said frame, a second sign frame, a spring plate integral with said second frame said spring plates having a curvature incongruent with the periphery of said post, a common strap extending around said post and extending over said spring plates and through said first and second sign frames, and adjustable securing means to tighten said strap around said post and hold said spring plates in a deflected position.

4. A sign for use in the combination as defined in claim 1 comprising a substantially planar sign frame, a spring plate extending laterally from the plane of said frame, a side of said frame to be adjacent the post to which said frame is to be secured, said spring plate being integral with said side and curved to provide a surface incongruent with the surface of the post when the plate is unstressed, whereby a strap passed around said post and over said laterally extending spring plate will stress said plate in a curvature more congruent with the surface of the post to take up stretching of the strap and provide lateral support for the sign frame when the strap is tightened.

5. A sign for use in the combination as defined in claim 1 comprising a sign frame comprised of a metal strap having a T-section and formed into a rectangle having an inwardly directed central flange along three sides, the fourth side being adapted to be secured to the post, a spring plate integral with the fourth side of the sign frame and extending laterally of the plane of the frame, said spring plate being curved to a substantially cylindrical surface incongruent with the surface of the post to which the sign frame is to be attached, whereby said spring plate will be stressed and provide lateral support for the sign frame when a strap is tightened around the post and the fourth side of the sign frame.
